UNITED STATES PATENT OFFICE.

LOUIS A. FLEURY, OF INDIANAPOLIS, INDIANA.

PNEUMATIC JACK.

1,374,295.

Specification of Letters Patent. Patented Apr. 12, 1921.

Application filed April 28, 1919. Serial No. 293,235.

To all whom it may concern:

Be it known that I, LOUIS A. FLEURY, a citizen of the United States, residing at Indianapolis, in the county of Marion and State of Indiana, have invented certain new and useful Improvements in Pneumatic Jacks, of which the following is a specification.

My invention relates to improvements in pneumatic jacks of the character disclosed in Letters Patent No. 1,295,471, issued to me February 25, 1919, and consists in certain details of construction and arrangements of parts whereby I am enabled to produce such an article in a more simplified and consequently less expensive form.

In the accompanying drawing, forming a part hereof, Figure 1 is an elevation of my improved jack structure showing its lifting chamber in collapsed condition; Fig. 2, a view partially in section taken on the dotted line 2, 2, in Fig. 1, and showing the lifting chamber inflated; Fig. 3, a plan on the dotted line 3, 3, in Fig. 1; Fig. 4, a horizontal sectional view looking in the direction of the arrows 4, 4, in Fig. 2; and Fig. 5 is an elevation showing the lifting chamber in modified form.

In said drawing the base of my improved jack is indicated by the numeral, 5, to which base is secured a frame, 6, which may comprise a single or plurality of preferably arched standards, 7. Where I employ a single frame member the same is provided with a central opening, but where a greater number are used I prefer to turn up the ends, 8, thereof and secure therebetween a sleeve, 9, in which opening or sleeve, as the case may be, I mount a vertical adjustable lifting member or jack, 10, provided at its upper end with a seat, 11, and having at its lower end a base, 12. One or more of the sides of said lifting member may be provided with a ratchet, 13, with which a pawl, 14, mounted upon the sleeve 9 or otherwise, may be engaged. Between the frame base 5 and the base 12 of the lifting member I insert a single collapsible chamber, 15, composed of any suitable material which may permit of its expansion and collapse and which is provided with an air inlet and exhaust valve, 16, for the admission and exhaust of air under pressure. In Fig. 2 I have shown said chamber 15 as spherical in form, and in Fig. 5 the same is spheroidal in form, but I do not desire to be under-

stood as limiting myself to any specific form, as it will be readily understood that I may employ a single chamber of any appropriate contour or design for the purpose.

It will be noted that the chamber 15 is loosely retained between the two bases 5 and 12, but it is obvious that either the upper or lower or both sides of said chamber may be flexibly secured to the bases. By loosely confining the same in the manner indicated I am enabled to readily withdraw the chamber for the purposes of repairing or renewal, and by a slight curved formation of the bases said chamber is positively held in proper position for performing its function of raising and lowering lifting member 10.

As in my former patent referred to, my improved jack in collapsed condition as indicated in Fig. 1 is placed under the vehicle or other object to be raised. Compressed air from any suitable source of supply is then introduced into chamber 15 through the valve, 16, which causes said chamber to distend and at the same time gradually raise lifting member 10, which latter in turn raises the object to which it is applied. To insure that said jack shall be maintained in positive position in its upward travel and thus steadily hold its load, the pawl and ratchet arrangement as indicated is provided as a means for accomplishing this, but it will be understood any appropriate arrangement for the purpose may be employed. When it is desired to lower the vehicle the pawl or other retaining means is released and the valve 16 adjusted to permit the escape of air from chamber 15, when the latter collapses so that member 10, indicated in raised position in Fig. 2, is caused to assume its lowermost position as shown in Fig. 1.

While I have shown two frame members for telescopically supporting the lifting member 10, it will be understood that one may be employed, but by employing two or more frame members they constitute in effect a cage for retaining the chamber 15 should there be any tendency of the latter to become displaced through irregular motion or accident.

I claim as my invention:

1. In a fluid actuated jack, a base, an arch-shaped frame secured thereto, a lifting member, movably mounted in said frame, and a flexible chamber for supporting and actuating said member.

2. In a fluid actuated jack, a base, a frame constituting a retaining cage secured to said base, a lifting member movably mounted in said frame, and a flexible chamber mounted within said cage between said base and member for operating the latter.
3. In a lifting jack, the combination, of a base, a frame secured thereto, a single sub-

stantially spherical collapsible chamber mounted on said base and within said frame, 10 a lifting member extensibly and retractably mounted in said frame and seated on said spherical chamber, and means for controlling the movement of said lifting member.

In testimony whereof I affix my signature. 15
LOUIS A. FLEURY.
